UNITED STATES PATENT OFFICE.

FRANK S. CROWELL, OF TOLEDO, OHIO, ASSIGNOR TO THE EDWARD N. RIDDLE COMPANY, OF TOLEDO, OHIO, A CORPORATION OF OHIO.

LIGHTING FIXTURE.

Application filed February 12, 1925. Serial No. 8,682.

My invention relates to that class of lighting fixtures which are suspended from a ceiling. In devices of this kind, with which I am familiar, two workmen are required, one to hold the fixture while the other is connecting the wires on the fixture to the wires issuing from the outlet or junction box.

My invention has for its principal object the improvement of the canopy and suspension devices.

A further object is to entirely eliminate the necessity for more than one workman, the structure being such that he will have the use of both of his hands while the conductors are being connected.

A further object is to provide means whereby the fixture will hang vertically, regardless of the inequality of the point of union between the outlet or junction box and the ceiling.

My means for accomplishing the foregoing objects may be readily understood by reference to the accompanying drawings which are hereunto annexed and are a part of this specification, in which—

Fig. 1 is a side elevation of my improved canopy and suspension device;

Fig. 2 is a vertical section of the device as shown in Fig. 1;

Fig. 3 is a vertical section showing the means of sustaining the fixture (not shown) while the conductors are being connected; and,

Fig. 4 is a bottom view of the canopy with the chain omitted.

Similar reference numerals refer to similar parts throughout the entire description.

As shown in the drawings, the outlet or junction box 11, which is of standard construction, is provided with a central stud 12 upon which is mounted a coupling 13. This coupling has depending from it a threaded rod 14. A canopy 15, of any desired configuration, is placed in the position illustrated. This canopy 15 has both ends open, but is provided with a strap 16 which is cast, or formed, therewith, and is provided with a central opening through which the threaded rod 14 passes. A nut 17 is mounted upon the said rod 14 and serves to draw the canopy 15 tightly against the ceiling.

The canopy 15 is provided with a cap or cover 18, which is held in position by means of screws 19 and 20 which are mounted in the strap 16 adjacent the wall of the canopy

15. This cover 18 is provided with an eye 21 in which is mounted a chain 22, of the usual construction employed for sustaining lighting fixtures. The provision of the eye 21 insures the fixture hanging vertically under all circumstances. Openings 23 and 24 are provided in the cover 18 on each side of the eye 21 for the passage of the wire conductors 25 and 26 leading from the lighting fixture (not shown). These wires are 65 suitably connected to the house wires 27 and 28 leading from the outlet or junction box 11. At one side of the strap 16, adjacent the central opening through which the rod 14 passes, I cast, or form, an upwardly extending member 29 which forms a hook 70 which is adapted to receive a link 30 of the chain 22.

In mounting a fixture of this kind, the operator first screws the coupling 13 on to 75 the stud 12 in the outlet or junction box 11. The canopy 15 is then slipped up over the downwardly depending threaded rod 14, this rod passing through the opening in the strap 16. The canopy 15 is locked in position by means of the lock nut 17. The house wires 27 and 28, extending from the outlet or junction box 11, are then pulled down through the canopy 15, as clearly seen in 80 Fig. 3. The chain 22, from which the lighting fixture (not shown) is depending, is then lifted, and the link 30 is hooked on to the hook 29 on the strap 16. In this position it will be apparent that the operator can release the fixture (not shown) and employ 85 both hands for the purpose of connecting the house wires 27 and 28 to the fixture wires 25 and 26. After being connected and taped in the usual manner, the wires can then be pushed up into the canopy 15, as clearly 90 shown in Fig. 2.

The link 30 is then detached from the hook 29, and the cover or cap 18 on the end of the chain 22 is slid up and over the heads of screws 19 and 20, openings 31 and 32 being 100 provided for this purpose. The cover 18 is also provided with arcuate slots 33 and 34, leading from the openings 31 and 32. These slots are fitted to the body of the screw, so as to permit the rotating of the cover 18 105 until the body of screws 19 and 20 enter slots 33 and 34, which being narrower in width than the diameter of the heads of screws 19 and 20, serve to secure the cover 18 so that the workman can have both 110

hands free to tighten the screws 19 and 20, and thus complete the installing of the fixture.

It will be apparent from the foregoing description that I have overcome the necessity for a second workman to hold the fixture while the house wires are being connected to the fixture wires, and also that this construction insures the fixture being suspended vertically.

Although I have shown and described a specific form of construction, it will be understood by persons skilled in the art, that numerous changes may be made, and I do not desire to be understood as limiting myself to the specific details thus illustrated and described.

Having thus described my invention, what I regard as new and desire to secure by United States Letters Patent is:

1. The combination with a lighting fixture of an outlet box, a threaded rod which depends therefrom, a canopy having both ends open, a strap which extends across the lower opening, there being a central opening in said strap through which said rod passes, a nut on said rod which holds said canopy against the ceiling, a cover for the lower end of said canopy, said cover having an eye therein, a chain linked in said eye, a hook on said canopy adapted to hold said chain while the fixture is being wired, said holding means being independent of the securing means for the fixture, and means to secure said cover to said canopy.

2. The combination with a lighting fixture

of a junction box, a canopy secured thereto, a cap for said canopy, means to secure a chain to said cap, means to secure said cap to said canopy, and means integral with said canopy to engage one of the links of a chain, said means being independent of the securing means for the fixture.

3. The combination with a lighting fixture of a junction box, a coupling secured thereto, a rod which depends therefrom, a canopy mounted on said rod, means to hold said canopy in position, a cover for said canopy having an eye formed therein, a chain mounted in said eye, a hook on said canopy adapted to hold said chain while the fixture is being wired, said holding means being independent of the securing means for the fixture, and means to secure said cover to said canopy.

4. The combination with a lighting fixture of an outlet box, a threaded rod depending therefrom, a canopy, a strap across the lower end thereof, there being an opening in said strap through which said threaded rod passes, a lock nut on said rod to hold the canopy in position, a cover for the lower end of said canopy, screws mounted in said canopy, there being openings in said cover adapted to register with the heads of said screws, and slots adjacent said openings to permit said cover to be rotated when in position, a chain linked into an eye formed on said cover, a hook adapted to hold a link of said chain, said means being independent of the securing means for the fixture.

FRANK S. CROWELL.
